(57) **CLAIM**

The ornamental design for an electronic device with animated icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view an electronic device with animated icon showing a first image of the claimed design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is a front view of an electronic device with animated icon showing a first image of another embodiment of the claimed design;

FIG. 9 is a second image thereof;

FIG. 10 is a third image thereof;

FIG. 11 is a fourth image thereof;

FIG. 12 is a fifth image thereof;

FIG. 13 is a sixth image thereof; and

FIG. 14 is a seventh image thereof; and,

FIG. 15 is a front view of an alternative electronic device showing the animated icon of FIG. 1 applied thereto. The animated icon designs of FIGS. 2-14 may be similarly applied thereto.

The dashed broken lines in the figures show an electronic device having a display screen, or an alternative electronic device having a display screen, and form no part of the claimed design. The dot-dash broken lines in FIG. 15 show a boundary of the animated icon that forms no part of the claimed design.

The appearance of the animated image sequentially transitions between the images shown in FIGS. 1-7 and FIGS.

(Continued)

8-14. The process or period in which one image transitions to another forms no part of the claimed design.
